(57) **CLAIM**

The ornamental design of an image for a computer display, as shown and described.

DESCRIPTION

FIG. 1 is a front perspective view of an image for a computer display according to the present invention;

FIG. 2 is a front view thereof, on an enlarged scale; and, FIG. 3 is a front view of a second embodiment thereof, on an enlarged scale.

The broken line drawings of a computer display monitor in FIGS. 1, 2, and 3 are for illustrative purposes only and form no part of the claimed design.
